CLAIM

The ornamental design for an outdoor lighting system transformer pedestal, substantially as shown and described.

DESCRIPTION

FIG. 1 is a perspective view of an outdoor lighting system transformer pedestal embodying the design of the present invention showing unclaimed environmental structure for purposes of illustration.

FIG. 2 is a perspective view of an outdoor lighting system transformer pedestal illustrated in FIG. 1.

FIG. 3 is a front side elevational view of an outdoor lighting system transformer pedestal illustrated in FIG. 1.

FIG. 4 is a back side elevational view of an outdoor lighting system transformer pedestal illustrated in FIG. 1.

FIG. 5 is a right side elevational view of an outdoor lighting system transformer pedestal illustrated in FIG. 1.

FIG. 6 is a left side elevational view of an outdoor lighting system transformer pedestal illustrated in FIG. 1.

FIG. 7 is a top view of an outdoor lighting system transformer pedestal illustrated in FIG. 1; and,

FIG. 8 is a bottom view of an outdoor lighting system transformer pedestal illustrated in FIG. 1.

Dot-dash broken lines used in FIG. 1 depict environmental subject matter that forms no part of the claimed design. Evenly spaced broken lines depict portions of the outdoor lighting system transformer pedestal that form no part of the claimed design.

1 Claim, 7 Drawing Sheets
